(57) **CLAIM**

The ornamental design for a storage bin as shown and described.

DESCRIPTION

FIG. 1 is a top perspective view of the storage bin; FIG. 2 is a side perspective view of the storage bin of FIG. 1; FIG. 3 is another top perspective view of the storage bin of FIG. 1;

FIG. 4 is a bottom perspective view of the storage bin of FIG. 1;

FIG. 5 is another bottom perspective view of the storage bin of FIG. 1;

FIG. 6 is a front elevational view of the storage bin of FIG. 1, the back elevational view being identical;

FIG. 7 is a left elevational view of the storage bin of FIG. 1, the right elevational view being identical;

FIG. 8 is a top plan view of the storage bin of FIG. 1; FIG. 9 is a bottom plan view of the storage bin of FIG. 1; FIG. 10 is a top perspective view of the storage bin, with two partitions inserted;

FIG. 11 is a top plan view of the storage bin of FIG. 10; FIG. 12 is an exploded view of the storage bin of FIG. 10; FIG. 13 is a top perspective view of the storage bin, with one of the two partitions inserted;

FIG. 14 is a top plan view of the storage bin of FIG. 13; FIG. 15 is a top perspective view of the storage bin, with the other one of the two partitions inserted;

FIG. 16 is a top plan view of the storage bin of FIG. 15; and, FIG. 17 is an exploded view of the storage bin of FIG. 15.
